UNITED STATES PATENT OFFICE.

DANIEL COLLEN, OF INWOOD, CANADA.

RAILWAY-CROSSING.

SPECIFICATION forming part of Letters Patent No. 571,215, dated November 10, 1896.

Application filed April 2, 1896. Serial No. 585,937. (No model.)

To all whom it may concern:

Be it known that I, DANIEL COLLEN, of Inwood, in the county of Lambton, Province of Ontario, and Dominion of Canada, have invented a new and Improved Railway-Crossing, of which the following is a full, clear, and exact description.

The object of the invention is to provide a new and improved railway-crossing arranged to provide continuous rails for the easy and safe passage of the wheels of a train and at the same time providing danger-signals for approaching trains in case the crossing is open.

The invention consists principally of crossing-rails made slideable for opening and closing the crossing or diamond.

The invention also consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement. Fig. 2 is an enlarged plan view of the switch mechanism on one arm of the crossing, and Fig. 3 is a sectional side elevation of the same on the line 3 3 of Fig. 2.

The improved railway-crossing is provided with two tracks A B, of which the track A is provided at the diamond with the fixed rail-sections A' A² and the track B is provided with similar fixed rail-sections B' B². The rail-section A' is adapted to be engaged at its ends by slideable rails A³ A⁴ for forming a continuous rail at the crossing, and the fixed rail-section A² may likewise be abutted at its ends by slideable rails A⁵ A⁶. The point of the rail A³ rests on the fixed rail-section A⁷, terminating in a switch-point A⁸, adapted to connect with and disconnect from the permanent track-rail A⁹. The slideable rail A⁴ is adapted to connect at its point with a permanent track-rail A¹¹, and the point of the slideable rail A⁶ is in engagement with a fixed rail-section A¹², terminating in a switch-point A¹³, adapted to open and close on the permanent track-rail A¹⁴. Now it will be seen that when the several parts described are in the position illustrated in Fig. 1 then continuous track-rails for the track A are provided, so that a train

can readily pass over the track A, said train having continuous rails for the crossing.

The track B is similarly arranged, that is, the rail B' in the diamond is adapted to receive at its ends the slideable rails B³ B⁴ and the other rail, B², is adapted to receive at its ends the slideable rails B⁵ and B⁶. The slideable rail B³ engages with its point the permanent rail-section B⁷, terminating in its outer end in a switch-point B⁸, adapted to open and close on the permanent track-rail B⁹. The slideable rail B⁴ is adapted to engage with its point the permanent track-rail B¹¹, and the slideable rail B⁵ is adapted to engage with its point the permanent track-rail B¹⁰. The slideable rail B⁶ is adapted to engage with its point the permanent rail-section B¹², terminating at its outer end in a switch-point B¹³, adapted to open and close on the permanent track-rail B¹⁴.

Now in order to move the movable parts of the tracks A and B for opening or closing either of the tracks at the crossing I provide the following mechanism for each track, said mechanism being under the control of the operator located in a tower near the crossing: Under the track A is arranged a transverse shaft C, and a similar shaft C' is arranged under the track B, and both shafts can be operated by the operator in the tower. On the shaft C are secured the double arms D D', connected by rods E E', respectively, with the outer ends of a bar F, carrying the inner ends of the slideable rails A³ A⁵. Similar rods E² E³ extend from the arms D D' to connect with a bar F', carrying the ends of the slideable rails A⁴ A⁶. Thus when the slideable rails A³ A⁴ A⁵ A⁶ are in an innermost or closed position, as shown in Fig. 1, that is, abutting on the permanent rail-sections A' A², and the operator turns the shaft C, then the arms D D' impart simultaneously a sliding motion to the bars F F', so that the slideable rail-sections are moved longitudinally away from the permanent sections A' A². In doing so the outer point ends of said slideable rail-sections A³ A⁵ and A⁴ A⁶ move out of alinement with the rail-sections A⁷, A¹⁰, A¹¹, and A¹², respectively, and consequently the rails of the track A are not continuous at the crossing. When the shaft C is then again turned in the opposite direction, the slideable rail-sections move

inward to again form continuous track-rails at the crossing, as shown in Fig. 1.

In order to hold the points of the slideable rail-sections $A^3 A^5$ and $A^4 A^6$ in proper relation to the fixed rail-sections above mentioned at the time the track is continuous, I provide arms $G G'$, which extend from the bar F and carry blocks $G^2 G^3$, adapted to engage the outer ends of the slideable rail-sections

- 10 $A^3 A^5$, said arms G being pivotally connected with links $H H'$, respectively fulcrumed in the rail-sections $A^{10} A^9$, respectively. Now it will be seen that when the bar F moves outward the arms $G G'$ are swung inwardly to permit
- 15 the points of the slideable rails $A^3 A^5$ to move inward, and when the tie F moves back to its former position then the arms $G G'$ swing outwardly and their blocks $G^2 G^3$ rest against the inner sides of the slideable rails to bring
- 20 their points again in proper alignment with the permanent rails $A^7 A^{10}$. A similar arrangement is made on the other arm of the track A , in that the bar F' is pivotally connected by arms $G^4 G^5$ with links $H^2 H^3$, respectively fulcrumed on the track-rails A^{14} and A^{11} , respectively. Blocks $G^6 G^7$ are held
- 25 on the arms G^4 and G^5 to engage the inner sides of the slideable rails $A^4 A^6$ and press the latter in contact with the fixed rail-sections
- 30 $A^{11} A^{12}$ to form a continuous track with the same. Thus the blocks serve as locking devices for the slideable rails to hold the latter in alignment with the adjacent permanent rail-sections.

- 35 In order to operate the switch-point A^8 , I pivotally connect the same near its free end with a transversely-extending link I , pivotally connected with a link I' , engaged by the slotted end of a link J , pivoted to the tie F . When the latter moves outward, as previously described, then the link J imparts a swinging motion to the link I' , and the latter moves the link I transversely, so that the switch A^8 is thrown into an open position at
- 40 the time the slideable rails $A^3 A^5$ disconnect from the permanent rail-sections $A' A^2$.

- 45 The outer end of the link J is pivotally connected with a link J' , fulcrumed on one of the ties, and said link J is also pivotally connected with a link K , carrying a signal L , the said link K being pivotally connected with a link K' , fulcrumed on one of the ties. When the bar F moves outward, as previously described, then the signal L is shifted and set
- 50 to a danger position, to warn a train approaching the crossing on the track A in the direction of the arrow a' that the track is open at the crossing.

- 55 The switch-point A^{13} is pivotally connected near its free end with a transversely-extending link I^2 , connected with a link I^3 , operated from a link J^2 , pivoted on the tie F' , said link J^2 being also connected with a link K^2 , carrying a signal similar to the one on the link K . The link K^2 is controlled by a link K^3 , pivoted on one of the ties.

When the bar F' moves outward simulta-

neously with the bar F , as previously explained, then the switch-point A^{13} is swung away from the permanent track-rail A^{14} at the same time the signal L on the link K^2 is set at "danger," so that a train approaching the crossing on the track A in the direction of the arrow b' is warned of the danger, as the track is open at the crossing. The same arrangement as in reference to the track A is made on the track B for moving the slideable rails $B^5 B^3$ and $B^4 B^6$ inward or outward from ties $F^2 F^3$, respectively connected by links E^4 , E^5 , E^6 , and E^7 , respectively, with double arms $D^2 D^3$ on the shaft C' .

The switch-points B^8 and B^{13} are actuated from the bars $F^2 F^3$ in the same manner as the switch-points $A^8 A^{13}$ are operated from the bars $F' F'$, respectively, and consequently further description of this mechanism is not deemed necessary. Furthermore, the slideable rails $B^3 B^5$ and $B^4 B^6$ are locked in place when closed by blocks similar to the blocks $B^2 B^3 B^6 B^7$, previously described in reference to the slideable rails $A^3 A^5 A^4 A^6$, the only difference being that those blocks for the slideable rails $B^3 B^5$ and $B^4 B^6$ are actuated from the bars $F^2 F^3$.

The signals L (see Figs. 2 and 3) are arranged at the approaches of the track B to the crossing, so as to warn approaching trains on the track B in case there is danger, or to give the said train the signal that the track is continuous over the crossing.

Having thus fully described my invention, I claim as new and desire to secure by Letters Patent—

1. A railway-crossing, comprising fixed rail-sections at the diamond, and endwise-movable rails at opposite sides of the diamond and in longitudinal alignment with the fixed rail-sections thereof, substantially as and for the purpose set forth.

2. A railway-crossing comprising fixed rail-sections at the diamond, and endwise-movable rails at opposite sides of the diamond in longitudinal alignment with the fixed rail-sections thereof, said movable rails being between the fixed sections of the diamond and the track-rails, substantially as described.

3. A railway-crossing comprising fixed rail-sections at the diamond, and pairs of endwise-movable rails at opposite sides of the diamond and in longitudinal alignment with the rail-sections thereof, each pair of slideable rails being adapted to connect at their outer ends with the track-rails, substantially as described.

4. A railway-crossing comprising track-rails, fixed rail-sections at the diamond, endwise-movable rails at opposite sides of the diamond and in longitudinal alignment with the rail-sections thereof, and intervening the said rail-sections and the track-rails, and means for moving the said slideable rails into and out of contact with the ends of the fixed rail-sections, substantially as described.

5. A railway-crossing, comprising perma-

5 nent rail-sections at the diamond of the crossing, and slideable rails adapted to abut on said permanent sections or be moved outwardly and away therefrom, each pair of slideable rails being adapted to connect at the outer point end with the permanent rail-sections of the track, a switch-point and means for moving the switch-point in unison with the slideable rails, substantially as shown and described.

6. In a railway-crossing, the combination with fixed rail-sections at the crossing, and fixed track-rails, of longitudinally-aligned rails having their inner ends abutting the fixed 15 rail-sections and their outer ends engaging the sides of the track-rails, means for moving the said rails longitudinally, and means for holding the outer ends of the said rails against the track-rails when their inner ends 20 abut the fixed sections of the crossing, substantially as described.

7. In a railway-crossing, the combination with fixed rail-sections at the crossing, of a bar fitted to slide, rails carried by said bar in 25 longitudinal alinement with the rail-sections, arms pivoted to the said bar and provided with blocks engaging the outer ends of the said rails, links pivoted to the arms and to the rail-sections of the track-rails, and means 30 for sliding said bar, substantially as and for the purpose set forth.

8. In a railway-crossing, the combination with fixed rail-sections at the crossing, of a bar fitted to slide, rails carried by the bar in 35 longitudinal alinement with the said sections

and having their outer ends pointed and engaging the sections of the track-rails, a rock-shaft provided with arms, rods connecting the arms with the said bar, arms pivoted to the slide-bar and having their outer ends 40 provided with blocks engaging the said rails, and links pivoted to the sections of the track-rails and to the outer ends of the said arms, substantially as described.

9. In a railway-crossing, the combination 45 with fixed rail-sections at the crossing, of movable rails alined with the said sections, and having their outer ends engaging the sections of the track-rails, means for moving said alined rails endwise and their outer ends 50 out of alinement with the track-rails, a switch-point, and means for operating the switch-point from the sliding bar, substantially as described.

10. In a railway-crossing, the combination 55 with fixed rail-sections at the crossing, of movable rails alined with the said sections and having their outer ends engaging the sides of the sections of the track-rails, means for moving the said alined rails endwise away 60 from the rail-sections and the sections of the track-rails, a switch-point, means for operating said point from the rail-operating mechanism, a signal, and means for operating the signal from the mechanism operating the 65 switch-point, substantially as described.
